UNITED STATES PATENT OFFICE.

ENOCH CHASE, OF MILWAUKEE, WISCONSIN.

BRICK OR OTHER KILN.

SPECIFICATION forming part of Letters Patent No. 338,036, dated March 16, 1886.

Application filed September 14, 1885. Serial No. 177,001. (No model.)

To all whom it may concern:

Be it known that I, ENOCH CHASE, of Milwaukee, in the county of Milwaukee, and in the State of Wisconsin, have invented certain 5 new and useful Improvements in Brick and other Kilns; and I do hereby declare that the following is a full, clear, and exact description thereof.

My invention relates to brick and other 10 kilns, and will be fully described hereinafter.

In the drawings, Figure 1 is a front view of a kiln embodying my invention. Fig. 2 is a section on line *y y*, Fig. 3. Fig. 3 is a section on line *x x*, Fig. 1. Fig. 4 is a detail.

15 A are the main walls of my kiln.
B are the combustion-chambers.

C are the jackets which surround the combustion-chambers, and are separated from the outer portion of the chambers by air-spaces *a*.
20 B' are flues which lead from the open air into the spaces *a*.

b are openings leading from the spaces *a* into the combustion-chambers at their rear.

D are the smoke-passages which lead from 25 the combustion-chambers into the kiln.

The air to feed combustion in the combustion-chambers is drawn in from beneath the grates E, and after the fire has been sufficiently started the vacuum created in the kiln proper 30 by the heat causes a rush of air through the chamber-spaces *a*, which joining with the smoke as it passes through the combustion-chambers into the kiln proper vitalizes it and

causes it to consume. The heat radiating from the jackets C serves to raise the temperature of the air that passes through the spaces *a* to a very high temperature, and therefore when this air joins with the smoke in the smoke-passage there is immediate combustion.

40 I prefer to bind the walls of my kiln by wooden uprights F, those in front passing through openings F' between the combustion-chambers, these openings being so large that the uprights will not come in contact with the 45 masonry.

Having thus fully described my invention, what I claim as new, and desire to secure by Letters Patent, is—

1. In a kiln, a furnace surrounded by air-spaces, in combination with openings leading from the open air into the air-spaces and other openings from the air-spaces into the rear of the furnace.

2. The combination of the chambers B, having air-spaces *a*, openings B' and *b*, the latter opening into the rear of the furnace, and smoke-passages D; with the kiln A, as set forth.

In testimony that I claim the foregoing I have hereunto set my hand, at Milwaukee, in 6c the county of Milwaukee and State of Wisconsin, in the presence of two witnesses.

ENOCH CHASE.

Witnesses:

S. S. STOUT,

H. G. UNDERWOOD.
